UNITED STATES PATENT OFFICE.

CHARLES E. EGAN AND HENRY F. GRAY, OF COLUMBUS, OHIO.

WATCHMAN'S TIME-RECORDER.

SPECIFICATION forming part of Letters Patent No. 428,583, dated May 20, 1890.

Application filed July 5, 1889. Serial No. 316,560. (No model.)

To all whom it may concern:

Be it known that we, CHARLES E. EGAN and HENRY F. GRAY, citizens of the United States, residing at Columbus, in the county 5 of Franklin and State of Ohio, have invented a certain new and useful Improvement in Watchmen's Electric Time-Registers, of which the following is a specification.

Our invention relates to that class of watchmen's time-recording devices wherein electrical connections are formed between various stations and a recording device arranged to operate in conjunction with clock-work; and the objects of our invention are to provide a 15 simple and inexpensive device of this kind by means of which an accurate and reliable record of the watchman's visits to the stations will be recorded; to so construct the same as to prevent the record of a given 20 number only from one station; to provide such mechanism at the receiving-station as to prevent the necessity of using more than two magnets for receiving from any number of stations; to obviate the necessity of using 25 separate sets of wires in forming the connections between each sending-station and the receiving-station, and to admit of the mechanism being so arranged and constructed as to prevent the watchman from knowing what 30 number is being recorded from any given station, and to so construct said mechanism as to operate the registering device by closing the circuit between the sending and receiving station. These objects we accomplish in the manner illustrated in the accompanying drawings, in which—

Figure 1 is a face view of one of the sending-station boxes and its mechanism. Fig. 2 is a plan view of the same. Fig. 3 is a face 40 view of the recording-disk, showing a rear side view of the needle-block. Fig. 4 is a plan view of the registering apparatus. Fig. 5 is a transverse section taken on line xx of Fig. 4. Fig. 6 is a side elevation of the 45 magnets shown in Fig. 4, and showing the connection of the same with the battery and binding-posts. Fig. 7 is a front end view of the mechanism shown in Fig. 4, and Fig. 8 is a vertical longitudinal section of the sliding 50 needle-box. Fig. 9 is a vertical longitudinal

section of the upper magnet at the receiving-station, showing the connection therewith with the trip-rod.

Similar letters refer to similar parts throughout the several views.

Referring to Figs. 1 and 2 of the drawings, A represents a station-box or rear frame-plate, which is preferably formed of wood, and A' the box-cover. To the frame-plate A is secured an ordinary alarm-work mechanism, consisting in the usual manner of a key-post a , actuated by a spring a' , and operating in the usual manner a number of gear and pinion wheels mounted on shafts which have their forward bearings in a metallic front 65 plate B.

Projecting outwardly from the upper portion of the plate B, above and on opposite sides of the key-post a , are two short metallic pins b b' . Projecting upwardly from 70 the outer projecting portion of the key-post a is a metallic finger b^2 , which normally rests between the pins b and b' and against the former, as shown in Fig. 1 of the drawings.

Fixed on the outer projecting end of the 75 shaft C, outside the plate B, is a circuit-closing disk c , having projecting from its periphery one or more teeth c' . The number of said teeth c' differs in the corresponding disk of each sending-station; but for the sake of 80 illustration we have chosen, as shown in the drawings, that disk having four teeth. This disk-carrying shaft C also carries on the inner side of the plate B a gear-wheel D and a pinion D', to which rotary motion is imparted 85 in the usual manner from a gear-wheel on the key-post.

Secured to the outer face of the plate B at a point on one side of the disk c is a non-conducting bar d . Secured to the upper side 90 of this insulating-bar d is one end of a metallic spring-strip d' , the remaining end of which projects over the end of said insulating-bar and terminates in such position over the disk c as to cause the contact therewith of the 95 disk-teeth c' when said disk is rotated, as hereinafter described.

d^2 represents a metallic plate secured to the face of the sending-station frame-plate at a point above the mechanism thereof, said plate 100

having an outwardly-projecting spring-strip arm d^3 , the outer end of which overhangs the projecting key-post, as shown.

Sending-stations having the above-described construction are designed to be located at the different points to be visited by a watchman, said sending-stations being connected, as hereinafter described, with the registering mechanism of the receiving-station.

10 E represents the metallic oblong frame of the registering device, said frame consisting, approximately, of two end pieces connected by two parallel arms $e\ e'$. Between these arms $e\ e'$ are supported a pair of spool-magnets e^2 , the cores of which are connected in the usual manner. Made to extend transversely between the magnet-spools e^2 , and having its ends passing loosely through oppositely-located holes formed in the frame-pieces $e\ e'$, is a sliding arm or pin e^3 . That outer projecting portion of the arm e^3 which projects through the frame-arm e' has fixed thereon an armature-bar e^4 . The opposite end of the pin e^3 supports on the outer side 25 of the frame-arm e , at the center of its length, a horizontal bar F. The outer end of the pin e^3 on the outer side of its armature-bar e^4 has pivotally connected therewith one end of a forwardly-extending lever-bar f, said lever-bar projecting over the forward end of the frame-plate E adjoining one side thereof. This lever-bar f is further pivoted on the frame-plate E by means of a pin f', made to project upwardly from said frame-plate through a 30 slotted opening formed in the lever.

The forward end of the frame E is provided, adjoining the side opposite that on which is located the lever f, with a forward extension f², within which is pivotally supported a short 40 vertical pin or shaft f³, which carries on its upper end a ratchet-wheel f⁴, and beneath said ratchet-wheel and adjoining said frame-extension a pulley-wheel f⁵, which is rigidly connected with the under side of said ratchet-wheel. Pivotally connected with the lever f at a point above the forward end of the frame E is one end of a pawl-arm G. This pawl-arm extends transversely above the forward end of the frame E and has its outer 45 end engaging with the teeth of the ratchet f⁴. This outer pawl end is normally held in engagement with one of said ratchet-teeth by means of a coiled spring G', the latter having one of its ends secured to the forward portion of said pawl G, and having its remaining end secured to the outer end of an arm g, the latter projecting forwardly from the forward end of the frame E. This projecting arm g is also connected with the outer projecting 50 end of the lever f by means of a coiled spring g'. This coiled spring, as will be seen, operates to draw the forward end of the lever f toward the ratchet-wheel sufficiently to hold the rear end of the lever f outward, and thus 55 normally to support the sliding pin e^3 in such position as to prevent the contact of the ar-

mature e^4 with the magnets e^2 and hold the bar F in close proximity to the frame-arm e.

Beneath the pawl G, near its connection with the lever f, is pivoted to the frame E one end of a second pawl g², the forward end of which, passing beneath said pawl G, is held in engagement with the same tooth of the ratchet f⁴ as that engaged by the pawl G. This lower pawl is normally held in this position by 70 means of a coiled spring g³, having its ends secured, respectively, to said lower pawl and the frame-arm g.

The frame-plate E has its ends projecting outwardly on that side on which is located 80 the bar F, and the outer ends of said projections are connected by means of a metallic track-strip H.

h represents a sliding block movably supported on the track-strip H by having the latter passing loosely through a T-groove in the bottom of the former. This block h has formed therewith an outwardly-projecting barrel h'. Extending longitudinally through said block and its barrel is a central needle-hole h², said hole being of greater circumference in the block than in its barrel, thus forming a shoulder h⁴ therein, as shown. Through this hole h² passes loosely a pin or needle h³, having its outer end pointed, and being of a 90 slightly greater length than the block and barrel, as shown. Fitted in the rear end of the pin-hole is a suitable plug, which loosely surrounds the pin or needle. Between this end plug and the internal shoulder h³ is made 95 to surround the pin a coiled spring i.

The pointed forward end of the pin or needle is normally sheathed within the barrel h'.

Secured to the pulley-wheel f⁵ and adapted to be wound thereon is one end of a cord I. 105 This cord passes, as shown, to the block h, to which it is secured, while a similar cord J is secured to the opposite side of said block, from whence it passes rearwardly, and running over a pulley-wheel j, supported on the 110 rear end of the plate E, it passes downwardly and supports on its lower end a suitable weight K.

L represents a vertical frame-arm, which is made to project upwardly from the rear end 115 of the frame-plate E to a point above the height of the magnets e². Supported against the flat front face of the arm L is the rear end of a spool-magnet l, which extends forwardly over and at right angles with the magnets e². 120 This upper magnet l has formed in its front end, as shown in dotted lines in Fig. 4 of the drawings, a pin-socket. Into this pin-socket is inserted loosely the upper horizontal portion of a wire trip-rod k, which is bent downwardly at a point on the outer side of the magnet end, and has its lower end bent to loosely embrace the pawls G g². Fixed on the upper horizontal portion of said wire rod k, at the point where its downward bend is 125 made, is a metallic armature-disk k', which, owing to the normal position of the pawls, is 130

normally held at a slight distance from the upper magnet.

M represents a thin disk, preferably formed of paper, and having its outer face printed to represent the dial-face of a clock. This paper dial is secured in any desired manner to the hour-hand post m of ordinary clock-works, and is adapted to be turned by said hand-post. The clock-works supporting said paper dial, as described, are so situated, as shown in Fig. 4 of the drawings, as to support the dial in close proximity to the outer pivoted end of the needle h³.

Supported at a point preferably above the recording apparatus are three binding-posts O, P, and Q.

From the metallic front plate B of each sending-station runs upwardly a short wire q, which connects near the sending-station with a wire q', the latter connecting with the binding-post Q, from whence it passes to battery R. From the metallic contact-strip d' of the sending-station extends upwardly a wire o, which connects with a wire o', the latter connecting with the binding-post O, from whence it passes to one of the magnet-spools e². A wire o² continues the connection to the remaining magnet e², and from the latter a wire o³ runs to the battery R. From the metallic plate d² a short wire p runs to a wire p', which connects with binding-post P. From the binding-post P the wire p' connects with one end of the magnet l, the remaining end of said magnet being connected with the battery-wire o³ by a wire p². The wires o', p', and q' may be continued past any number of sending-stations and connected with each of said stations in the manner above described. These wires terminate, however, at the last sending-station by being connected directly with the parts d', d², and B.

The operation of our device is as follows: The sending-station boxes may be arranged in different rooms or different parts of a building, or at other different points, as may be desired, the construction of the mechanism of said sending stations differing only in the number of contact-teeth c' formed on the disk c. The receiving-station and its mechanism may be located at an office, residence, or other desired point, and is connected with said sending-station, as above described. As is usual in this class of devices, the watchman is instructed to visit the points occupied by the sending-stations at certain hours or fractions thereof. For illustration, we will suppose the watchman to have reached the sending-station herein illustrated and described at three o'clock. Being provided with a suitable key, he engages the same with the key-post a, which projects through an opening s in the mechanism cover, and turns said key-post until its finger b² comes into contact with the pin b'. The key then being withdrawn, the tension thus given the spring a' of the alarm mechanism will cause the key-post and the gear-wheels and shafts of the

clock-work operated thereby to be rotated to their former positions. This movement of said gear-wheels will operate through the consequent movement of the shaft C to rotate the disk c one revolution, thus bringing the contact-teeth c' successively into contact with the projecting outer end of the contact-strip d'. As each of said contact-teeth meets said contact-strip, it will be seen that a complete circuit will be formed between the metallic front plate B, (with which said disk is connected by its shaft,) through magnets e² and the battery R and the contact-strip d', by means of the wires q q' and o o' o² o³. In this manner the cores of the magnets e² will be alternately magnetized and demagnetized as the contact-teeth c' are connected and disconnected from the strip d'. At each closing of the circuit thus produced the armature e⁴ will be drawn toward the magnets, which movement will operate through the sliding pin e³ to force outward the bar f and cause the latter to strike the projecting rear end of the needle h³. This blow upon said needle will be sufficient to drive its pointed end into the paper disk M. This movement of the armature and sliding pin will operate to draw inward the rear end of the lever f, resulting in the outward movement of the forward portion of said lever, said outward movement operating to draw the pawl G sufficiently outward to cause its engagement with the next tooth of the ratchet f⁴. The magnets e² being again demagnetized by the passage of the disk-tooth from the contact-spring, the force of the spring g' will operate to draw the sliding pin e³ again back to its former position. This movement of said sliding pin will not only result in the release of the armature from the magnets and the release of the spring-actuated perforating-needle from contact with the hammer-bar F, but will also cause the pawl G to resume its normal position, and in so doing slightly rotate the ratchet-wheel f⁴. While the pawl G is traveling to a new tooth of the ratchet it will be seen that the spring-actuated pawl g² will remain in engagement with the notch just vacated by the pawl G until the upper pawl has by the breaking of the circuit and tension of the spring g' sufficiently rotated the ratchet-wheel as to allow the lower pawl to drop into the same notch with the upper pawl, thus preventing the ratchet being rotated when the upper pawl is traveling to a new tooth. This partial rotation of the ratchet-wheel f⁴ will cause a slight portion of the cord I to be wound upon the pulley f⁵. The forward movement of the cord I thus produced will cause the needle-block h to travel slightly forward on its track H, so that when the above-described movement of the parts is repeated by the contact of the next tooth of the disk c with the contact-strip d' the perforations formed by the pointed end of the needle will be slightly removed from the one previously formed. As

shown in the drawings, we may employ a guide-plate V, the latter being secured at one end to the rear end of the frame E, and having its outer portion bent in a line parallel with and on the outer side of the track H. This guide-plate is provided with a central longitudinal slot, and is adjusted to form a rear bearing for the paper-dial. It will be observed that, the paper-dial disk being fixed 10 on the outer projecting end of the hour-hand post of the clock, said dial would be rotated by said post at the same speed with which the latter moves. This paper dial is so set with relation to the perforating-needle point 15 as to cause the perforations made by said needle-point to be formed in alignment with the figures or marks on said disk representing the time when said perforations were made.

Owing to the fact that there are four contact-teeth formed on the disk c, herein shown, it will be observed that four perforations but slightly removed one from the other will be formed in a line opposite the figure on the dial indicating three o'clock, thus showing 25 that the watchman visited the station having the four-toothed disk at exactly three o'clock.

The arm d³ of the plate d² of the sending-station mechanism is so located as to cause the key-post finger b² to come into contact 30 with the lower end of said arm d³ while traveling between the stop-pins b b'. This contact of the finger b² and arm d³ will, through the plate d², wire p, wire p', binding-post P, wire p² and its connection with the battery, and 35 the battery-wire q' and its connection with the metallic frame-plate of the sending-station clock-work, form a complete circuit through the upper magnet l, the core of which becoming thereby magnetized will 40 cause the armature-disk k' to be drawn against said magnet end, which movement will, through the wire trip-arm k, force the pawls G and g³ from their engagement with the ratchet-wheel. Thus it will be seen that, 45 the needle-block h having been drawn forward on its track-plate H by a previous recording operation, as above described, and the ratchet-wheel being released from the pawls, the weight K will operate to draw the 50 needle-block to the rear end of its track, the ratchet and its reel being rotated to unwind from the latter the cord I. It will be seen that the needle is now again supported in position to perform its office of recording. 55 The finger b² being released from contact with the arm d³, and the core of the magnet l being thereby demagnetized, the tension of the springs G' and g³ will operate to withdraw the pawls outward and cause their 60 engagement with the teeth of the ratchet.

It will be seen that the office of the magnet l is to release the ratchet from engagement with the pawls and allow the needle to assume an operating position. It will also 65 be observed that the sending-station-mechanism boxes may be so arranged with reference to the route taken by the watchman

that the number of perforations will not be produced in their regular order—that is, the first number recorded may be five and the second number eight or any other desired number, according to the arrangement of the boxes. 7c

The person or persons having control of the mechanism at the receiving-station may be provided with a list of the numbers which should be recorded in order. The sending-station mechanism being covered in the usual manner by a cover plate or cap, the watchman will be unable to discover what number should be registered by each box, thus preventing any possibility of the mechanism of any one box being so manipulated by the watchman as to produce at the receiving-station the different numbers of perforations in the order in which they should be received. 85

By the herein-described construction and operation it will be observed that but two sets of magnets may be used for the operation of any number of sending-stations, and that the necessity of using a separate set of wires for the connection of each sending-station with the receiving-station is obviated, but three main wires being used. It will also be observed that the construction and operation of the herein-described mechanism are such as to render at all times a reliable and durable record, and that the record is so produced as to admit of an accurate record of the watchman's service being kept on file. 95

From the construction herein shown it will 100 also be seen that although the wires o' p' q' are used as conductors for all sending-stations, but one sending-station will be in connection with the recording mechanism at one time.

Owing to the fact that the circuit remains open and the battery is not in use when the sending-stations are not being operated, it will be seen that the durability and strength of the battery will not be impaired when the device 110 is not in use. 105

Having now fully described our invention, what we claim as new, and desire to secure by Letters Patent, is—

1. In a watchman's time-register, the combination, with one or more sending-stations, each provided with alarm mechanism, their toothed contact-disk c, contact-strips d', and key-posts b², of the receiving-station magnet c², connected through a battery with said sending-station frame-plate and spring-strip by wires, said magnet supported in suitable frame E, sliding pin e³, its armature-bar e⁴, and hammer-bar F, pivoted spring-actuated lever f, pivoted and spring-actuated pawls G 115 and g³, pivoted ratchet f⁴, pulley f⁵, connected therewith, frame track-plate H, needle-block h, adapted to slide therein and having internal spring-actuated registering-needle h³, cord I, connecting-pulley f⁵ and said needle-block, 120 and cord J, connecting the opposite side of said block with a weight K, substantially as and for the purpose specified. 125

2. The combination, with a magnet-support-

- ing frame having horizontal track-plate H, of the pivoted ratchet and pulley wheels f^4 f^5 , the teeth of the former engaged by pivoted and spring-actuated pawls G and g^2 , the former im- 5 parting rotary motion to said ratchet and pulley through a pivoted and spring-actuated lever f, operated by the armature of a magnet which is alternately magnetized and demag- netized, a sliding needle-block h, mounted on track H, containing a spring-actuated perfor- 10 rating-needle, said block being connected on opposite sides respectively, as described, with the pulley f^5 and weight K by cords, substan- tially as and for the purpose set forth.
- 15 3. In a watchman's time-register, the com- bination, with the sending - station alarm mechanism, toothed disk c, rotated thereby, and contact spring-strip d', of the magnet e², supported on frame E, sliding pin e³, its ham- 20 mer-arm F, and armature e⁴, lever f, pivoted and spring-actuated, as described, pivoted and spring-actuated pawls G g^2 , pivoted ratchet and pulley wheels f^4 and f^5 , sliding needle- 25 block h, having internal spring-actuated need- 30 le h³, said block loosely mounted on frame- track H, and connected on opposite sides, re- spectively, with pulley f^5 and weight K, a paper 35 dial M, supported and rotated by the hour-hand of a clock-movement in close prox- imity to the needle-point, and wires connect- 40 ing the spring-strip and frame of the sending-station mechanism with the magnet e² through the battery R, substantially as and for the purpose specified.
- 35 4. The combination, with the registering- mechanism plate E, its magnet e², sliding pin e³, carrying armature e⁴, and hammer-bar F, as described, pivoted and spring-actuated lever f, pivoted and spring-actuated pawls G 45 and g^2 , pivoted ratchet f', and pulley f^5 , need- 50 le-block h, movably supported on track H, and connected on opposite sides, respectively, 55 with pulley f^5 and weight K by cords, of the upper or tripper magnet l, trip-rod k, its upper portion loosely entering a socket in said 60 magnet-core and its lower portion embrac- 65 ing pawls G g^2 , and armature-disk k', sup- ported on said rod, substantially as and for the purpose set forth.
5. In a watchman's time-register, the com- 70 bination, with a sending-station alarm mech- anism, a contact-plate d², a finger b², pro- jecting from the key-post of said clock-move- 75 ment and adapted to be brought into contact with plate d² or an arm thereof when rotated, 80 contact-strip d', and toothed disk c, rotated by said clock-movement, of the receiving- 85 station magnets e², sliding pin e³, carrying ar- mature e⁴, and hammer-bar F, pivoted and 90 spring-actuated lever f, pivoted and spring- 95 actuated pawls G and g^2 , pivoted ratchet f', and pulley f^5 , needle-block h, having internal 100 spring-actuated needle h³, said block movably supported on said track H, and connecting on opposite sides, respectively, with pulley f^5 and weight K by cords I and J, a paper dial M, supported and rotated by the hour-hand post of a clock-movement in close proximity to the pointed end of the needle, tripper-mag- 105 net l, trip-rod k, its upper portion loosely en- 110 tering a socket in said upper magnet-core and its lower portion embracing pawls G and g^2 , armature-disk k', supported on said trip- 115 rod, wire p', connecting the plate d² and tri- 120 pper-magnet l through a battery, and wires o' 125 q', respectively connecting contact-strip d' and the metallic frame of the sending-station 130 mechanism with the magnet e², substantially as and for the purpose specified.
